A. A. Briesew

UNITED STATES PATENT OFFICE.

WILLIAM J. SCHONECK, OF BROOKLYN, NEW YORK.

ARTIFICIAL LEG.

1,284,473.

Specification of Letters Patent. Patented Nov. 12, 1918.

Application filed June 25, 1918. Serial No. 241,768.

To all whom it may concern:

Be it known that I, WILLIAM J. SCHONECK, a citizen of the United States, and a resident of Brooklyn, in the county of 5 Kings and State of New York, have invented certain new and useful Improvements in Artificial Legs, of which the following is a specification.

This invention relates to an artificial leg 10 of novel construction, and more particularly to novel means for permitting the flexible band or "shrinker" to be readily tightened up on the stump to compensate for the shrinkage of the latter.

15 In the accompanying drawing:

Figure 1 is a side elevation of an artificial leg embodying my invention;

Fig. 2, a longitudinal section thereof;

Fig. 3, an enlarged cross section on line

20 3—3' Fig. 1;

Fig. 4, an enlarged section on line 4—4' Fig. 3, and

Fig. 5 a section through a leg adapted for knee amputations.

25 The artificial leg comprises a lower leg section 1, a thigh section 2, and a foot 3. The foot is provided with an upwardly extending tenon 4, engaging a centrally disposed mortise 5, formed in the bottom of 30 section 1 and opening into the upper socketed portion 6 thereof. The width of section 1 is of substantially uniform diameter for some distance up, while the height of the mortise should exceed that of the tenon.

35 In order to reduce the height of the leg at the ankle a corresponding piece is sawed off the lower end of section 1 and then tenon 4 is inserted into mortise 5 and is glued thereto. Owing to the fact that mortise 5

40 opens into socket 6, tenon 4 is free to project into the latter, when the length of the leg is reduced to a considerable extent, thus obviating the necessity of cutting off the tenon.

45 The thigh section 2 is connected to the leg section 1, by an additional knee section 7 which is pivoted to the latter at 8. A rod 9 pivoted to the knee section at 10 extends into the hollow of section 1, and there engages a rubber stirrup 11, suspended within section 1 by a strap 12, so as to impart to the leg while walking the necessary muscle action. Knee section 7 is provided at its upper end with an annular flange or projection 13, engaging a lower mortise 14, of 50 thigh section 2, said mortise opening at its

upper end into the upper socket 15 of said thigh section. If the leg is to be shortened at the thigh, the lower end of the thigh section 2 is cut off to the extent desired, and 60 flange 13 is glued into mortise 14. A reinforcing plate 16 may be sunk across the joint and screwed to the knee and thigh sections, while an additional dowel pin 17 may be passed through the thigh section 2 65 and flange 13.

Within the upper socket 15 of thigh section 2 is fitted a tubular band or "shrinker" 18, the upright edges or flanges 19 of which overlap to a considerable extent. At a distance back of each of such edges there are 70 connected to the band, a plurality of straps 20, arranged one below the other, and adapted to be passed through two upright rows of correspondingly arranged openings 75 21 formed in thigh section 2. Opposite straps 20 the band is provided with a pair of additional straps 22 passing through openings 23 of thigh section 2, and constituting an anchorage for the band. Directly 80 after amputation, the stump is swollen to a maximum width and is fitted into its socket 15 without the use of any band. After the stump has shrunken in course of time, the band is fitted into the thigh section, straps 85 20 of one flange are crossed by the straps of the other flange and are passed through the opposite line of openings 21. The straps are drawn out, so as to tighten the band upon the stump to the extent desired, by 90 increasing the overlapping portions of the band, and then each pair of horizontally aligned straps is tied together, so as to retain the band in its adjusted position. In this way, the diameter of the band may be regulated in a simple and effective manner, while 95 the band will be securely held in position after being adjusted.

It will be seen that by the construction described, the band in all of its adjustments 100 will completely encompass the stump, without leaving an objectionable gap. Its protruding straps 20 permit it to be readily set, and when set, the straps not only serve to hold the band in its selected position, but 105 also to securely hold it to the thigh section 2. Finally, the anchoring straps 23 secure the band to the thigh section at a point opposite to the tying straps, prevent shifting, may be more or less slackened to effect a 110 recentering of the band, and permit its removal whenever necessary.

In case of knee amputations, the band, constructed as described, is fitted into the socket 6 of the lower leg section 1 as illustrated in Fig. 5.

5 I claim:

An artificial leg comprising a socketed member having two upright rows of apertures and a pair of additional apertures, a

band having overlapping edges, straps secured to said band at a distance back of said edges and adapted to be passed crosswise through said rows of apertures, and additional anchoring straps secured to the band, and adapted to be passed through said additional apertures.

WILLIAM J. SCHONECK.
